180° H-PLANE BEND FOR RECTANGULAR WAVEGUIDE

John F. Reuvers, Santa Ana, James U. Clark, La Habra, and Edward W. Lockhart, Buena Park, Calif., assignors to Hughes Aircraft Company, Culver City, Calif., a corporation of Delaware

Filed Oct. 23, 1961, Ser. No. 148,305

9 Claims. (Cl. 333—98)

This invention relates to microwave devices and more particularly to a rectangular waveguide structure which effects a 180° bend in the H-plane.

A conventional H-plane bend for rectangular waveguide generally constitutes two sections of waveguide having a common narrow side and a semicircular termination extending from the outer narrow sides. The construction of this type of H-plane bend, however, is somewhat difficult to realize in that it is generally desirable to employ investment castings which inherently have several significant shortcomings. Performance requirements, for example, may dictate tolerances which are sufficiently rigid as to make the castings very difficult to produce in quantity. In addition, the castings often show tendencies toward warpage when subjected to a dip brazing process which may be necessary to incorporate the bend into a more extensive waveguide system.

It is therefore an object of the present invention to provide an improved 180° H-plane bend in rectangular waveguide having a low voltage standing-wave ratio over a broad range of frequencies.

Another object of the present invention is to provide a 180° H-plane bend for rectangular waveguide that is comparatively simple to manufacture.

Still another object of the present invention is to provide a 180° H-plane bend for rectangular waveguide that has a low insertion loss over a broad range of frequencies.

A further object of the present invention is to provide a 180° H-plane bend for rectangular waveguide that requires a minimum amount of space.

In accordance with the present invention, the narrow sides of first and second rectangular waveguide sections are disposed adjacent and coextensive each other and are separated by a conductive spacer which may be several times the thickness of the waveguide wall. A shorting plane is disposed across the extremities of the waveguide and a rectangular aperture placed through the adjacent narrow sides of the waveguide and the spacer in the vicinity near and normal to the shorting plane. This aperture is slightly reduced in height from that of the waveguide to achieve rigidity and simplicity of manufacture. This reduction in height, however, introduces capacitive reactance which, in turn, is neutralized by shortening the aperture to the extent that an equal and opposite amount of inductive reactance is introduced. Lastly, inductive elements are disposed symmetrically about each 90° bend in a manner to render the bend reflectionless over a wide range of frequencies. In a preferred embodiment of the invention, inductive irises are employed in which case the placement and penetration are chosen to render the bend reflectionless.

In the operation of the 180° H-plane bend of the present invention, the rectangular aperture of the present invention appears resonant over a broad range of frequencies, the width of which is enhanced by the conductive spacer. In addition, the 90° bend in either waveguide appears as a shunt capacitance at the plane of its bend. This shunt capacitance, together with the shunt inductance of the inductive elements, produces resonance through the remainder of the H-plane bend.

The above-mentioned and other features and objects

2

of this invention and the manner of obtaining them will become more apparent by reference to the following description taken in conjunction with the accompanying drawings, wherein:

5 FIGURE 1 is a perspective view, partially cut away, of a preferred embodiment of the invention;

FIG. 2 is a plan sectional view of the device of FIG. 1;

FIG. 3 is a view of section 3—3' of FIG. 2; and

FIGS. 4 and 5 are perspective views of alternate embodiments of the device of the present invention.

10 Referring now to FIGURE 1 of the drawings, a preferred embodiment of the present invention includes sections 10, 12 of rectangular waveguide, the extremities only of which are shown. The section 10 of rectangular

15 waveguide has parallel narrow sides 13, 14 and parallel broad sides 15, 16. Similarly, the section 12 of rectangular waveguide has parallel narrow sides 17, 18 and parallel broad sides 19, 20. The narrow sides 14, 17 of the sections 10, 12 of rectangular waveguide, respectively, are disposed adjacent and coextensively and are separated with a conductive I-beam spacer 22. The internal height of the I-beam spacer 22 is made equal to the external width of the narrow sides 14, 17 thereby to accommodate both sections 10, 12 and separate the narrow sides 14, 17 by only the thickness of the vertical portion of I-beam spacer 22, as viewed in the drawing. The I-beam spacer 22 extends back from the extremities of the sections 10, 12 of rectangular waveguide by an amount greater than the width of section 10 or 12. A rectangular aperture

20 24 is then disposed through the adjacent narrow sides 14, 17 of sections 10, 12 of rectangular waveguide, respectively, and through the I-beam spacer 22. The aperture 24 commences at a distance equal to the width of the waveguide sections 10, 12 from the extremities thereof

25 and continues toward the extremities for a distance substantially equal to 90% of the width of the waveguide section 10 or 12. The height of the rectangular aperture 24, on the other hand, is of the order of 80% of the inner height of the sections 10, 12 of rectangular waveguide and is disposed symmetrically therein. In general, a length of the rectangular aperture 24 that is less than the width of the waveguide sections 10, 12 introduces an inductive reactance and a height that is less than the height of the waveguide sections 10, 12 introduces a

30 capacitive reactance. It is nevertheless desirable to make the height of the rectangular aperture 24 sufficiently less than the height of the waveguide sections 10 or 12 for ease of manufacture and to achieve rigidity in the structure. The length and width of the rectangular aperture

35 24 are accordingly selected so as to introduce equal amounts of reactance and accordingly make the aperture 24 resonant. The characteristic of this resonance is broadened by the increased thickness of the aperture 24 produced by the I-beam spacer 22.

40 45 55 In addition to the foregoing, irises 26, 27 are inserted transversely into the waveguide sections 10, 12 from the narrow sides 13, 18, respectively, at corresponding points therealong which points occur within the center portion of the length of rectangular aperture 24. Further, irises 28, 29 are inserted longitudinally into the center portion of waveguide sections 10, 12, respectively, from the extremities thereof equidistant from the I-beam spacer 22. The lengths of the irises 26, 27, 28, 29 are substantially the same and are of the order of 25% of the width

50 55 60 65 of the rectangular waveguide section 10 or 12. Lastly, a shorting bar 30 is disposed across the common extremities of rectangular waveguide sections 10, 12 immediately adjacent extremities of the irises 28, 29. In order to increase the rigidity of the bend, shorting bar 30 may, for example, have a square cross section. Final assembly of the device may be achieved by employing a dip

70 75 80 85 90 95 brazing process to weld the respective elements together.

Referring now to FIGS. 2 and 3 of the drawings, there are shown sectional views of the device of FIG. 1 wherein in preferred dimensions and placement of the aperture 24 and irises 26, 27, 28, 29 are indicated. In particular, with waveguide sections 10, 12 each having a width "A" as shown in FIG. 2, the rectangular aperture 24 commencing from the extremities of the waveguide sections 10, 12 extends from 0.1A to A. The irises 26, 27 extend transversely inward commencing from the narrow sides 13, 18 at a distance of 0.5A from the extremities of the waveguide sections 10, 12 and the irises 28, 29 each extend inwardly from the shorting bar 30 longitudinally along the center line of the waveguide sections 10, 12, respectively. In each case the irises 26, 27, 28, 29 are of the order of 0.25A in length and extend for the entire distance between the broad sides 15, 16 and 19, 20 of the waveguide sections 10, 12, respectively. Referring to FIG. 3, on the other hand, wherein the distance between the broad sides 15, 16 or 19, 20 is designated "H," the height of the aperture 24 is designated 0.8H and is disposed equidistant from the broad sides 15, 16 and 19, 20.

Referring now to FIG. 4, there is shown an alternate embodiment of the device of FIG. 1 wherein the irises 26, 27, 28, 29 are replaced with conductive cylindrical posts 36, 37, 38, 39, respectively. The conductive cylindrical posts 36, 37, 38, 39 are generally disposed normal to the broad sides 15, 16, 19, 20, are of a diameter of from 0.1A to 0.25A; and are disposed with a diameter thereof coinciding with a line which corresponds to the position of the respective irises 26, 27, 28, 29 with the respective peripheries thereof butting up against the narrow sides 12, 13 and the shorting bar 30. This latter position is determined by the diameter of the respective conductive cylindrical posts 36, 37, 38, 39 in that different diameters correspond to different inductive reactances. The remainder of the device of FIG. 4 is similar to that of FIG. 1.

Referring to FIG. 5, there is shown an additional device in accordance with the present invention wherein the irises 26, 27, 28, 29 are replaced with semicircular conductive posts 40, 41, 42, 43, respectively. The respective semicircular conductive posts are generally of the same radius which is from 0.1A to 0.25A and are disposed with the flat sides thereof adjacent the narrow walls 13, 18 or the shorting bar 30 with the centers thereof placed at points corresponding to the junctions where the irises 26, 27, 28, 29 abut against the narrow walls 12, 13 and shorting bar 30. As before, the remainder of the device of FIG. 5 is similar to that of FIG. 1.

In the operation of a 180° H-plane bend of a type described in connection with FIG. 1, the losses for devices fabricated from dip-brazed aluminum are no more than an equivalent length of waveguide and the voltage standing-wave ratio over the entire S-band, i.e., 2800 to 4000 megacycles, is less than 1.10. Also, over a range of frequencies from 2930 to 3230 megacycles the voltage standing-wave ratio is less than 1.02.

Although the invention has been shown in connection with a certain specific embodiment, it will be readily apparent to those skilled in the art that various changes in form and arrangement of parts may be made to suit requirements without departing from the spirit and scope of the invention.

What is claimed is:

1. A microwave device comprising first and second sections of rectangular waveguide of predetermined height and width, a narrow side of said first section of rectangular waveguide being disposed adjacent and coextensive with a narrow side of said second section of rectangular waveguide; a longitudinal aperture joining said first section of rectangular waveguide with said second section of rectangular waveguide through said adjacent narrow sides; first and second inductive elements disposed in the

center region of the broad sides of said first and second sections of rectangular waveguide, respectively, at corresponding points therealong opposite one extremity of said longitudinal aperture; and third and fourth inductive elements disposed adjacent the remaining narrow walls of said first and second sections of rectangular waveguide, respectively, at corresponding points therealong opposite the center portion of said longitudinal aperture.

2. The microwave device as defined in claim 1 wherein in said longitudinal aperture presents substantially equal amounts of inductive and capacitive reactance throughout a broad range of frequencies.

3. The microwave device as defined in claim 1 which additionally includes means for providing a shorting plane transversely across said first and second sections of rectangular waveguide adjacent to said first and second inductive elements and on the side thereof opposite from said third and fourth inductive elements.

4. The microwave device as defined in claim 1 wherein said first, second, third and fourth inductive elements are conductive circular posts extending between the respective broad sides of said first and second rectangular waveguide sections.

5. The microwave device as defined in claim 1 wherein said first, second, third and fourth inductive elements are conductive semi-circular posts extending between the respective broad sides of said first and second rectangular waveguide sections, the flat side of said first and second inductive elements being normal to said longitudinal aperture and on the side of said semi-circular posts that is farthest therefrom, and the flat side of said third and fourth inductive elements being immediately adjacent the respective remaining narrow walls of said first and second sections of rectangular waveguide.

6. An H-plane 180° bend for rectangular waveguide comprising first and second sections of rectangular waveguide of predetermined height and width, a narrow side of said first section of rectangular waveguide being disposed adjacent to and coextensive with a narrow side of said second section of rectangular waveguide; means for providing a shorting plane transversely across said first and second sections of rectangular waveguide; a resonant aperture having a height and width less than said predetermined height and width, respectively, joining said first and second sections of rectangular waveguide through said adjacent narrow sides thereof adjacent said shorting plane; first and second conductive irises of a height substantially equal to said predetermined height disposed in the center region of said first and second rectangular waveguide sections, respectively, parallel to the longitudinal axis thereof commencing from said shorting plane and extending away therefrom on the same side as said resonant aperture; and third and fourth conductive irises of a height substantially equal to said predetermined height extending inwards from corresponding points of the remaining narrow sides of said first and second sections of rectangular waveguide, respectively, transversely to the longitudinal axis thereof and opposite the center portion of said resonant aperture.

7. The H-plane 180° bend for rectangular waveguide as defined in claim 6 wherein said first, second, third and fourth irises each have a substantially uniform length of from 0.15 to 0.40 times said predetermined width.

8. The H-plane 180° bend for rectangular waveguide as defined in claim 6 wherein said resonant aperture has a rectangular configuration.

9. The H-plane 180° bend for rectangular waveguide as defined in claim 8 wherein said rectangular configuration has a length of from 0.80 to 0.95 times said predetermined width and a height of from 0.7 to 0.9 times said predetermined height.
